Design No. 11,842, dated July 6, 1880.

UNITED STATES PATENT OFFICE.

DAVID McNAIR, OF BOSTON, MASSACHUSETTS, ASSIGNOR TO ROXBURY CARPET COMPANY, OF SAME PLACE.

DESIGN FOR CARPET.

SPECIFICATION forming part of Design No. 11,842, dated July 6, 1880.

Application filed May 22, 1880. Term of patent 3½ years.

To all whom it may concern:

Be it known that I, DAVID McNAIR, of Boston, in the county of Suffolk and State of Massachusetts, have invented a new and original Design for Carpets, of which the following is a specification.

The nature of my design is fully shown in the accompanying photographic illustration. It consists of an aggregation of barbaric figures, more or less irregular, thickly arranged on a plain ground, with the intervening spaces ornamented by a chintz-work of foliage.

I claim—

The design for a carpet, substantially as shown and described.

In testimony whereof I have signed my name to this specification, in the presence of two subscribing witnesses, this 19th day of May, A. D. 1880.

DAVID McNAIR.
